UNITED STATES PATENT OFFICE.

GIDEON J. JULIAN, OF BEVERLY, MASSACHUSETTS, ASSIGNOR TO UNITED SHOE MACHINERY CORPORATION, OF PATERSON, NEW JERSEY, A CORPORATION OF NEW JERSEY.

TRIMMING MACHINE.

Application filed August 31, 1925. Serial No. 53,642.

This invention relates to trimming machines and the invention is illustrated as embodied in a sole trimming machine of the type known as a "Planet sole rounder" in the use 5 of which a sole is clamped upon a stationary pattern and a rounding knife is caused to travel around the pattern to trim the sole. It will be understood, however, that in various aspects the invention is not limited to embodiment in machines of this type, being also applicable, for example, to machines in which the relative travel of a knife and a pattern 10 is secured by rotation of the pattern.

In machines of the Planet sole rounder type 15 the sole is supported in a horizontal plane and the rounding or trimming knife is pivoted to swing about a vertical axis so that its cutting edge may be kept in contact with the pattern throughout the travel of the knife. 20 The chip or string produced by the knife however, by hugging closely the edge of the work immediately behind the knife, may interfere more or less with the free swinging of the knife about its vertical pivot, particularly at the toe and heel of the sole, and 25 therefore may tend to prevent the cutting edge from following accurately the outline of the pattern.

One object of the present invention is to 30 prevent the chip or string from interfering with the free swinging movement of the trimming knife.

With this object in view, and in accordance 35 with one feature of the present invention, means is provided for deflecting the chip so as to provide ample clearance for the knife during the trimming operation. In the construction herein shown this means comprises a chip deflector which is carried 40 by the knife arm and is arranged to follow the knife so as progressively to deflect the chip outwardly on the plane of the work, and at a substantially constant angle from the trimming knife.

45 Another feature of the invention consists in the provision of a safety device in the nature of a knife guard for preventing injury to the operator's hands by cuts from the trimming knife. As shown, the knife guard 50 is carried by the chip deflector and is ar-

ranged to overlie the upper end of the knife so as to prevent the operator's hands from inadvertently coming in contact with the knife edge.

The invention will be more fully explained 55 with reference to the accompanying drawings in which one embodiment of the invention is illustrated as applied to a sole rounding machine of the same general type as that disclosed in Letters Patent of the United 60 States No. 1,506,839, granted September 2, 1924, on my application.

In the drawings:

Fig. 1 is a plan view of a chip deflector 65 constructed in accordance with the present invention, together with so much of a sole rounding machine of the type disclosed in the above-named Letters Patent as is necessary to illustrate the operation of the deflector;

Fig. 2 is a plan view of the deflector and 70 certain portions of the rounding machine shown in Fig. 1, the deflector and associated movable parts being shown in a different position with respect to the work; and

Fig. 3 is a perspective view of the parts 75 shown in Fig. 2.

As in the machine set forth in the Letters Patent referred to, the illustrated machine is provided with a fixed pattern 6 and a rotating knife carrier 8, the latter being supported upon the usual rotating circular table 10. A small portion of which is indicated at 10. The rounding knife 12 is carried by a yoke member pivotally mounted in the usual manner upon the inner end of an arm 14 secured to a segmental plate 16 which is pivoted at 18 to the table 10. The plate 16 is provided with a gear segment 20 engaged by a pinion 22 which is acted upon by a spring (not shown) tending to turn the pinion in a direction to press the knife against the pattern. The knife carrier 8 is moved in and out and is oscillated to change its angular position by two cranks 24 and 26 which are mounted upon the rotating table 90 10 and are connected with the knife carrier. The cranks 24 and 26 make two revolutions during the rounding of a sole, the result of this action being such that there will be a rapid swinging movement of the knife car- 95 100

rier to keep the direction of pull upon the knife approximately tangent to the pattern at the point of operation and also to vary the travel of the knife so that the carrier 5 will be swung through an angle while the knife is operating about the comparatively sharp curve at the heel or about the sharper curve at the toe.

The chip deflector, which is indicated at 16 30, is arranged to follow immediately behind the trimming knife as the latter travels around the pattern. To this end, the deflector 30 is carried at one extremity of an arm 32 the opposite forked end of which is 15 pivotally connected by means of a vertical stud 34 with the knife-carrying arm 14. To hold the deflector yieldingly against the pattern a spring-pressed plunger 36 carried by the arm 14 bears against a shoulder formed 20 on the deflector-carrying arm 32 and tends to swing the arm 32 inwardly toward the pattern. An adjustable stop screw 38, provided with a suitable locking nut 40, extends through the forked end portion of the arm 25 32 and bears at its inner end against a lug 41 on the knife-carrying arm 14 to limit the swinging movement of the arm 32 under the influence of the plunger 36 when the chip deflector is out of engagement with the pattern. 30

As shown, the chip deflector 30 is made in the form of an elongated wedge and is supported in a vertical position with its point or thin edge portion located immediately behind the heel of the trimming knife. The 35 chip deflector extends vertically from the horizontal plane of the upper end of the trimming knife to the bottom of the plane of the lower face of the pattern and the smooth inner face of the deflector is arranged to bear against the edge of the pattern and the trimmed edge of the sole. To enable the wedge to swing in the horizontal plane of the pattern so as to adapt itself to the curves 40 of the pattern the wedge is carried at the upper end of a stem 42 (Fig. 3) which is mounted in a vertical bearing in the arm 32. As shown, the stem 42 depends from the rear end of the deflector, which, being free 45 to rotate in conformity to its guiding surface, is tilted in passing a corner or an undulation to the extent that its apex, which deflects the trimmed strip, is maintained substantially in the plane of the outer surface of the trimming knife notwithstanding 50 the latter's independent rotation. In this manner the deflector compensates for the contour of the sole, and provides substantially the same relief for the knife irrespec- 55 tive of its position on the sole, since in passing a corner of the sole the deflector is rotated oppositely to but commensurately with the cutter. Normally the deflector is maintained in a position substantially parallel to 60 the plane of the trimming knife by the ac-

tion of a spring-pressed plunger 44 which is confined within a recess 46 in the arm 32 and is arranged to bear against a flattened surface 48 on the deflector stem 42. The plunger 44 yields to permit the deflector to 7 adjust itself readily so that the forward extremity of the deflector will be directed toward the trimming knife.

In operation, as the knife travels around the pattern, the chip deflector is constrained 7 to follow immediately behind the knife and by reason of its wedge shape the deflector functions to displace the string or chip produced by the knife sufficiently to relieve the pressure of the chip against the face of the knife and thus to permit the knife to swing as much as is necessary to insure that its cutting edge will be continually maintained in engagement with the edge of the pattern. By thus causing the knife edge accurately to follow the 85 contour of the pattern the sole will be trimmed accurately to a corresponding contour, there being no deviation of the knife from the contour of the pattern even at the sharply curved portions at the heel and toe. 90

The knife guard, indicated at 50 in Fig. 3, is carried by the deflector 30. As shown, the guard 50 comprises a plate which extends forwardly beyond the leading portion of the deflector sufficiently to overlie the upper end of the knife 12. The guard 50 is removably secured to the deflector 30 by means of a screw 52 and is held against edgewise displacement by means of a dowel pin 54. The forward extremity of the guard 50 is curved downwardly, as shown at 56, the better to guard the cutting edge of the knife. The width of the guard 50 is sufficient to insure that the swinging of the chip deflector will not remove the guard from operative position above the trimming knife, the knife being protected by the guard irrespective of the angular position of the deflector with respect to the knife. Since the guard 50 at all times completely covers the upper end portion of the trimming knife it functions to prevent the operator's fingers from being caught and cut by the knife should he inadvertently bring his hand down upon or in advance of the knife as he might do for the purpose of picking up the chip which is being trimmed from the sole. Upon removal of the screw 52 the knife guard 50 may be readily detached from the chip deflector for the purpose of facilitating the removal and replacement of the trimming knife. 110 115 120

Having thus described my invention, what I claim as new and desire to secure by Letters Patent of the United States is:

1. In a sole trimming machine, means for 125 trimming material from a sole, and means adapted for guidance by the sole and compensative therefor for deflecting said material from said trimming means.

2. In a sole trimming machine, the combination with a pattern and a knife relatively 130

movable to trim a sole clamped to the pattern, of means for deflecting the material trimmed from the sole by the knife to relieve the pressure of said material upon the knife during 5 the trimming operation.

3. In a sole trimming machine, the combination with a pattern and a knife relatively movable to trim a sole clamped to the pattern, of a chip deflector arranged behind the knife 10 to deflect the chip as it is being trimmed from the sole.

4. In a sole trimming machine, the combination with a pattern and a knife arranged to travel around the pattern to trim a sole 15 clamped to the pattern, of a chip deflector arranged to follow the knife.

5. In a sole trimming machine, the combination with a pattern, a trimming knife and a knife carrier movable to cause the knife to 20 travel around the pattern, of a chip deflector carried by the knife carrier and arranged progressively to deflect the chip trimmed from the sole by the knife.

6. In a sole trimming machine, the combination with a pattern and a trimming knife 25 relatively movable to trim a sole clamped to the pattern, of a chip deflector arranged behind the knife, and means for yieldingly holding the chip deflector against the pattern.

30 7. In a sole trimming machine, the combination with a pattern and a trimming knife relatively movable to trim a sole clamped to the pattern, of a chip deflector arranged behind the knife and yieldingly held in engagement with the pattern and being capable of tilting to vary its angular relation to the pattern at its point of contact therewith.

40 8. In a sole trimming machine, the combination with a pattern and a trimming knife relatively movable to trim a sole clamped on the pattern, of a chip deflector having a wedge formation adapting it to deflect the chip trimmed from the sole by the knife.

45 9. In a sole trimming machine, the combination with a pattern, a trimming knife and a knife carrier movable to cause the knife to travel around the pattern, of an arm pivoted to the knife carrier for swinging movements toward and from the pattern, and a 50 chip deflector carried by the arm and arranged behind the trimming knife.

55 10. In a sole trimming machine, the combination with a pattern, a trimming knife and a knife carrier movable to cause the knife to travel around the pattern, of an arm pivoted to the knife carrier for swinging movements toward and from the pattern, a chip deflector, and yielding means for acting upon the arm to hold the deflector against the 60 pattern.

65 11. In a sole trimming machine, the combination with a pattern, a trimming knife and a knife carrier movable to cause the knife to travel around the pattern, of a chip deflector pivotally mounted upon the arm for tilt-

ing adjustment relatively to the arm in the plane of the pattern.

12. In a sole trimming machine, the combination with a pattern, a trimming knife and a knife carrier movable to transfer the 70 knife around the pattern, an arm pivoted to the knife carrier for swinging movement toward and from the pattern, means for limiting the swinging movement of said arm, and a chip deflector carried by the arm arranged to follow the knife. 75

13. In a sole trimming machine, in combination, a pattern, a trimming knife, a knife carrier movable to transfer the knife around the pattern, a chip deflector carried by the 80 knife carrier and arranged to follow the knife, and yielding means for holding the chip deflector in a normal position substantially parallel to the knife.

14. In a sole trimming machine, the combination with a pattern and a knife arranged to travel around the pattern to trim a sole 85 clamped to the pattern, of means arranged to follow the knife and act upon the waste material trimmed from the sole, and a member carried by said means for guarding the cutting edge of the knife. 90

15. In a sole trimming machine, the combination with a pattern and a knife relatively 95 movable to trim a sole clamped to the pattern, of a chip deflector, and means carried by the chip deflector for guarding the knife. 95

16. In a sole trimming machine, the combination with a pattern and a knife relatively 100 movable to trim a sole clamped to the pattern, of a chip deflector arranged behind the knife, and a guard plate carried by the chip deflector and arranged to overlie the upper end of the knife to guard the cutting edge of the knife. 105

17. In a sole trimming machine, the combination with a pattern and a knife arranged to travel around the pattern to trim a sole clamped to the pattern, of a knife carrier, a chip deflector carried by the knife carrier 110 and arranged to follow the knife, and a knife guard secured to the chip deflector. 110

18. In a sole trimming machine, the combination with means for trimming material from a sole, and means for deflecting said 115 material while being trimmed, of means for guarding said trimming means.

19. In a sole trimming machine, means for trimming material from a sole, and means for deflecting said material during the trimming operation, said deflecting means being pivoted rearwardly of the trimming means, and arranged to engage along one side the material of the sole and to engage along the other side the material trimmed from the 120 sole. 125

In testimony whereof I have signed my name to this specification.

GIDEON J. JULIAN.
